C. H. WILLIAMS.
THIRD POINT SUPPORT FOR BRAKE BEAMS.
APPLICATION FILED MAY 8, 1916.

1,207,253.

Patented Dec. 5, 1916.

Inventor
C. Haines Williams
By J. H. Cornwall, Atty.

UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD-POINT SUPPORT FOR BRAKE-BEAMS.

1,207,253.

Specification of Letters Patent.

Patented Dec. 5, 1916.

Application filed May 8, 1916. Serial No. 96,093.

To all whom it may concern:

Be it known that I, CHARLES HAINES WILLIAMS, a citizen of the United States, residing at Chicago, Illinois, have invented a 5 certain new and useful Improvement in Third - Point Supports for Brake - Beams, of which the following is a full, clear, and exact description, such as will enable others skilled in the art to which it appertains to 10 make and use the same, reference being had to the accompanying drawings, forming part of this specification, in which—

Figure 1 is a side elevational view of my improved third point support. Fig. 2 is an 15 end elevational view of the same. Fig. 3 is a side elevational view of a modified form of third point support. Fig. 4 is an end elevational view of the same partly in section.

This invention relates to a new and useful 20 improvement in third point support brake beams, and is designed particularly as an improvement upon the type of third point support shown in patent to Posson, No. 789,879, dated May 16, 1905.

In the Posson construction, when the 25 brakes are applied, particularly with a new shoe, the end of the strut is sprung upward and out of position, this spring tending to twist the strut out of shape. The rigid link 30 forming a member of the parallelogram together with the brake lever, causes the shoe to first strike the tread of the wheel at the bottom, thereby producing an uneven wear. As long as the shoe continues to wear 35 evenly, the strut may be somewhat relieved and not distorted, but the tendency is, at all times, to cause heavier pressure at the bottom than at the top of the new shoe. This distorting movement, being produced 40 by rigid connections, cannot result otherwise than in an uneven wear of the shoe which at all times is objectionable.

My present improvement contemplates a 45 flexible link which will at all times support the brake beam so that it is capable of normal application, permitting the end of the strut to move downwardly, to adjust itself, when the brakes are applied. I have shown my improvement in the form of a flat spring 50 and coil springs, but it is obvious that other forms of yielding connections could be employed.

I am aware of United States Letters Patent to Robischung, No. 543,703, dated July 55 30, 1895, and also Patent No. 654,241, dated

July 24, 1900, to Francis, but in both of these patents the third point support, if it may be so called, is carried by the truck and is not in the form of a yielding connection between the strut and the connection 60 rod.

In the drawings, 1 indicates the end of the brake lever strut having a nose extension 1^a for the attachment of the third point supporting member.

2 is the connecting rod to which the brake lever, not shown, is pivotally connected, said 65 brake lever also being pivotally mounted in the strut and having its upper end connected to a pull rod, not shown, as is usual.

3 is a flat spring, preferably having an S-shaped bend in its middle and whose ends, arranged at the proper angle, are secured between washers 4 held in place by pins 5 and 6, passing through openings in the nose 75 1^a of the strut and the end of the connecting rod, respectively, as shown. When the

brakes are applied, the ends of spring 3, pivotally connecting the end of the strut and the connecting rod, will be compressed to 80 absorb the relative difference in the arc of movement of the brake supporting hangers, levers, etc. In idle position, the centers A and B are as indicated in Fig. 1. When the 85 brakes are applied, these centers would be moved to points A' and B', where a rigid link was employed, which would be an improper location of the center A'. The proper location of center of the strut eye should be at the point A'', to avoid uneven 90 wear of the shoe, and this proper location is attained by a slight compression of the spring 3 which permits the inner end of the strut to be drawn downward so that the face of a new shoe would bear evenly on the 95 tread of the wheel. The shoe can thus accommodate itself to the tread of the wheel without placing any distortional stresses on the brake beam during the time that the brakes are being applied and when the brake 100 beam is under load.

In Figs. 3 and 4, I have shown the modified form of third point support in which an eyed pin 7 is pivotally mounted to the strut, said pin being received in the sleeve 8 on 105 the cross connecting member 9, being surrounded by the spring 10 which presses upon said cross connecting member and a spring follower 11 adjacent the strut. A cotter pin 12 through the lower end of the 110

pin 7 holds the parts together. The cross connecting member is provided with a bearing 13 at its outer end for receiving a perforated eyed pin 14. A cotter pin 15 enables this pin 14 to be adjustably mounted in its bearing 13. The lower end of pin 14 is pivotally connected to the connecting rod 2. The operation of the structures shown in Figs. 3 and 4 is similar to that described with respect to Figs. 1 and 2, but the form shown in Figs. 3 and 4 possess the additional advantage of adjustment with respect to one of its connecting members.

It will be readily understood that minor changes in the size, form and construction of the various parts of my improved third point support for brake beams can be made and substituted for those herein shown and described, without departing from the spirit of my invention, the scope of which is set forth in the following claims.

I claim:

1. In a third point support for brake beams, the combination of a brake beam strut, a flexible third point support connected to said strut, and non-flexible means

constituting part of the brake rigging for supporting said third point support.

2. In a third point support for brake beams, the combination of a strut of a beam, a flexible third point support pivotally connected thereto, and a connecting rod to which the opposite end of said third point support is connected.

3. A third point support for brake beams comprising the combination of a brake beam strut, a connecting rod, and a yielding third point support connected to and carried by said strut and said rod.

4. A third point support for brake beams comprising the combination of a brake beam strut, a connecting rod, and a flat spring pivotally connected to said strut and said rod, said spring having a reverse bend in its length.

In testimony whereof I hereunto affix my signature in the presence of two witnesses, this 2nd day of May, 1916.

C. HAINES WILLIAMS.
